(57) CLAIM

The ornamental design for a seat frame, as shown and described.

DESCRIPTION

FIG. 1 is an isometric view of a first embodiment of the seat frame of my design;

FIG. 2 is a top plan view thereof;

FIG. 3 is a front elevational view thereof;

FIG. 4 is a left side elevational view thereof, the right side elevational view being a mirror image thereof;

FIG. 5 is a back elevational view thereof;

FIG. 6 is a bottom plan view thereof;

FIG. 7 is an isometric view of a second embodiment which view differs from FIG. 1 only by the broken line showing of side arms; and,

FIG. 8 is an isometric view of the first embodiment which view differs from FIG. 1 only by the broken line showing of a seat structure.

The broken line showing in the drawing figures is for illustrative purposes only and forms no part of the claimed design.
